SHUTTLELESS LOOM

William Pool, Spondon, England, assignor to
Celanese Corporation of America, a corporation
of Delaware

Application September 5, 1935, Serial No. 39,201
In Great Britain September 14, 1934

5 Claims. (Cl. 139—126)

This invention relates to shuttleless looms.

U. S. Patent No. 2,005,391 describes means for effecting weft selection in a shuttleless loom of the type in which weft is drawn in loop form from a supply prior to insertion into the warps, the particular description of the specification being directed to a loom having weft measuring apparatus capable of effecting a selection from four different wefts supplied at each or either side of the loom. Weft is presented to loop-drawing means by means of movable trapping means housed within gear boxes, which boxes contain the bulk of the mechanism for effecting the selection of the weft and for controlling the lengths of the weft loops and the release of the loops for insertion into the warps. Each gear box contains four rotatable members in the form of discs, each carrying a pair of trapping devices, and pivotally mounted latches operating in connection with notched members rotatable with said rotatable discs provide for the release of one of the discs and the locking against rotation of the remaining discs.

Pairs of pivoted latches are connected together by links to ensure that only one latch of each pair will be in position to lock its disc against rotation. Further means are provided to ensure that the drive to the gear box is transmitted only to the one disc free for rotation, differential mechanisms being employed to provide for the driving of all the discs from a common driving means.

One of the trapping devices on each disc is provided with a cutter to sever the weft after every other pick presented by that disc.

An endless chain has pivotally mounted on it pairs of loop-drawing carriers and selector means provide for one only of each pair of carriers being brought into operative position in relation to the disc selected to present weft for insertion. In connection with one of the discs means are provided to withdraw out of the path of the carriers the length of weft extending between an inserted pick and the disc during any interval elapsing before the drawing of a second loop from that disc.

According to the present invention, the disc-locking latches form part of a rigid, conveniently rectangular, frame-work, movement of the frame in one direction releasing one pair of discs while locking the other pair. The movement of the frame-work, which is guided by rollers engaging suitable slots, is effected by means of a cross-slide having a pair of inclined slots engaging pins on two side members of the frame-work, the

cross-slide being operated by means of a forked lever mounted on the end of a dobby-controlled sleeve extending into the gear box. The two latches for the upper pair of discs are spring mounted in the frame-work so that each of these latches has a sufficient movement to allow it slightly to enter its corresponding slot immediately the controlling sleeve moves. Should, therefore, the selector mechanism operating to transmit the drive to one freed disc only operate in advance of the cross-slide, the spring-loaded latches make certain that their respective discs cannot move forward and so cause a mis-change.

Other improvements in the latch mechanism and in the disc selecting mechanism and trapper construction will appear from the subsequent description with reference to the accompanying drawings, in which

Figure 1 is a front elevation, partly in section, of the mechanism of the instant invention incorporated in the gear-box assembly illustrated in Figure 6 of U. S. Patent No. 2,005,391;

Figure 2 is a plan view, partly in section, of the gear-box assembly, part of which is shown in Figure 1, and corresponds to Figures 5 and 7 of Patent No. 2,005,391;

Figure 3 is a front elevation, partly in section, of the gear-box assembly taken on the line 3—3 of the present Figure 4;

Figure 4 is a part sectional elevation looking at the left-hand side of Figure 3, and corresponds to Figure 22 of Patent No. 2,005,391; and

Figures 5 to 12 show, diagrammatically, the sequence of operations followed in inserting two consecutive connected picks in one disc of a gear-box.

A chain 5 drives a chain-wheel 6 of the gear-box 7 comprising upper and lower gear housings 21, 22 and side housings 23, 24 surrounding a tunnel-like space 25. In the lower and upper walls 26, 27 of the housings 21, 22 respectively are provided bearings 28a, 28b, 28c, 28d for spindles 29a, 29b, 29c, 29d to which are rigidly secured discs 30a, 30b, 30c, 30d within the tunnel 25, each of the pairs of discs 30a, 30b and 30c, 30d facing each other and each of the pairs 30a, 30c and 30b, 30d lying side by side.

In the subsequent description, similar parts associated with or operating in connection with each of the discs 30 are given the same reference numeral, and, where the description is applicable to each or all of the discs generally, such reference numeral is used alone. Where, however, the description relates to the operation of the member in connection with a particular disc, the ref-

erence numeral has added to it the suffix *a*, *b*, *c*, or *d* to correspond to the appropriate disc *30a*, *30b*, *30c*, or *30d*.

- On the ends of the spindles *29a*, *29b*, *29c*, *29d* within the housings, *21*, *22* are secured gears *31a*, *31b*, *31c*, *31d*, the gear *31a* being driven by gear *32a* loosely mounted on the vertical shaft *33*. Gears *31b*, and *31c* and *31d* are similarly driven from shafts *33* and *34*.
- At the upper ends of the shafts *33*, *34* are arranged differential gears *38*, *39* carrying helical gears *40*, *41* driven, as described in U. S. Patent No. 2,005,391, from the two sides of the differential *42* carrying the chain wheel *6*. By means of the drive through the three differential gears *38*, *39*, *42*, any one of the discs *30* can be driven while the others remain stationary.

Connected with each of the disc-driving gears *31a*, *31b*, *31c*, *31d* is a projecting rim *56a*, *56b*, *56c*, *56d* respectively, each having two notches *57* on the opposite sides of its periphery. A rectangular frame-work comprising horizontal members *60*, *61* and vertical members *62*, *63* lying in the housings *21* . . . *24* carries latches *64a* . . . *64d*, an upward movement of the frame releasing the upper discs *30a*, *30c* and a downward movement the lower discs *30b*, *30d*.

The frame is guided by rollers *65* engaging slots *66*, and its vertical movement is imparted by a cross-slide *67* guided by rollers *68* and slots *69*. In the slide *67* are two inclined slots *70* engaging pins *71* on the members *62*, *63* of the frame. The cross-slide is given endwise movements by a forked lever *72* mounted on the end of a sleeve *13* extending into the gear-box *7*, the lever *72* embracing a pin *74* on the slide *67*.

The latches *64a*, *64c* for the upper pair of discs *30a*, *30c* are urged downwards by springs *75a*, *75c*, so that each of these latches enters the corresponding notch *57* immediately the cross-slide *67* moves to change the operation from one of the upper discs to one of the lower discs *30*. The discs *30a*, *30c* then cannot move.

The top latches *64a*, *64c* are rectangular in shape and slightly less in width than the notches *57*. It is not necessary that the bottom latches *64b*, *64d* be spring-loaded; each of these, however, preferably has an inclined edge, as shown, to engage a correspondingly shaped notch to ensure that these latches are forced out of engagement with the notches should any mishance bring the latch-carrying frame into an intermediate position.

Spring-loaded plungers *76* are also fitted to engage the opposite slots *57* to those engaged by the spring-loaded latches *64* to centralize the upper discs *30a*, *30c*, thus eliminating the effect of any back-lash in the gearing. A single blade spring *77* serves to load both plungers. The other pair of discs *30b*, *30d* may similarly be fitted with spring-loaded plungers. The spring-loaded plungers also have the effect of easing the reaction load on the latches just at the moment that the drive changes from one disc to another.

The selection of the one of each pair of weft carriers *78* (on chain *5*) which is to remain inoperative is effected, as in U. S. Patent No. 2,005,391, by means of slides *79* carrying teeth *80a* . . . *80d*. These slides *79* are controlled by a lever *81* on the end of an extension *82* of a dobby-controlled spindle *83* which extends into the gear-box to provide for the drive of one disc only. A link *84* connects the lever *81* with a lever *85* operating one of the toothed slides *79* and a stirrup *86* connects that slide with the other so

that both slides move simultaneously in the same direction to one side or the other of the gearbox, and throw one carrier into inoperative position while permitting the other carrier to remain in the operative position into which it has previously been brought, as described in U. S. Patent No. 2,005,391.

Provision is made for independently loading the two trapping devices *87* on each disc *30*. For this purpose, the spindles *88* of the two trapping devices engage diametrically opposed notches *89* in a plate *90* loosely surrounding the bearing *29* of the disc *30*. Springs *91* located in recesses in the disc adjacent the spindles *88* force the plate *90* in such a direction that the trapping devices *87* normally remain closed. Cams *92* engaging the ends of the spindles open the trapping devices as required. The spring *91* adjacent the trapping device fitted with a cutter *93* is stronger than the other so as to ensure certain cutting of the weft as this device operates every other pick. As described in U. S. Patent No. 2,005,391, the cams operating the trapping devices may be adjustable to vary the time of operation. In addition, the gear wheels *32* driving the lower discs *30* may fit on a taper *94* on their driving shafts *33*, *34* so that these wheels may be rotated slightly on their shafts to provide a further adjustment of timing.

It has been found that the weft-withdrawing hook employed to withdraw the weft supplied by one of the discs (*30c*) out of the path of the carriers (and described in Patent No. 2,005,391 of which see Figures 23 to 28) effectively releases the weft when that disc is again in operation without the use of the control means described in U. S. Patent No. 2,005,391, since the trapping device cuts the withdrawn length of weft sufficiently near to the hook to allow the end of the length to run out of the hook. A simplified means to bring the hook into weft-engaging position comprises a symmetrical two-lift cam *95* (see Figure 2) mounted on the spindle *29c* of the corresponding disc *30c* and adapted to engage a roller *96* on a lever *97* in connection with the lever *98* which carries and operates the withdrawing hook. Since the weft-withdrawing hook is beyond the plane of Figure 3 it has been omitted from the figure for the sake of clarity. The above mentioned figures of Patent No. 2,005,391, however, give detailed illustration of the position and function of the hook.

Figures 5 and 12 show how, by modified working of the apparatus, the compensating mechanism of Figures 29-31 of U. S. Patent No. 2,005,391 may be dispensed with.

Figures 5 and 6 show the weft *99* held by its end in trapper A and then by the rotation of the disc *30* engaged by the trapper B. In Figure 7, a carrier *78* has drawn the weft between the trappers A and B into a loop, the weft running freely through trapper B. The loop *100* reaches its full size, as in Figure 8, and then is released from the carrier *78* and substantially simultaneously with such release is engaged by the dummy shuttle *101* moving from right to left. The dummy shuttle *101* inserts the weft as a pick *102* of the fabric *103*, leaving a length *104* extending from the edge *105* of the fabric to the trapper B (Figure 10). Meanwhile, the disc *30* continues its rotation, a carrier *78* drawing out a second loop *106*, which, as shown in Figure 11, is cut by the trapper A from the weft supply *99* before the carrier *78* has travelled as far as the traveller *75*.

in drawing the first loop 100 to its full extent (Figures 8 and 9).

The second loop 106 is therefore shorter than the first loop 100, the amount necessary to make 5 the second loop sufficient for a whole pick being made up by the length 104 connecting the second loop with the first loop, already inserted in the fabric.

After cutting of the second loop 106 by the 10 trapper A, the carrier 78 retains its hold on the loop though still travelling. This enables the length of the second loop between the carrier 78 and the trapper B to be kept under control until the dummy shuttle 101 engages the length 15 as shown in Figure 12, so as to insert it into the warps, the trapper B releasing the weft to end the cycle.

What I claim and desire to secure by Letters 20 Patent is:—

1. Weft-measuring apparatus of the type described, comprising four trapping means arranged in two pairs, four latches adapted to lock each of the four trapping means respectively, a rigid frame carrying the latches in pairs, and 25 means to move the frame in one direction or the other to free one pair of trapping means and lock the other.

2. Weft-measuring apparatus according to

claim 1, wherein one pair of latches is spring mounted in the rigid frame.

3. Weft-measuring apparatus according to 5 claim 1, wherein one pair of latches are rectangular in shape to engage correspondingly shaped but wider notches in the one pair of trapping means, and the other pair of latches have an inclined edge to engage and facilitate entry into correspondingly shaped notches in the other pair of trapping means. 10

4. Weft-measuring apparatus according to 15 claim 1, comprising a cross-slide, inclined slots and pins engaging therewith forming connections between the cross-slide and the rigid frame, and means for giving the cross-slide an endwise movement to operate the rigid frame.

5. Weft-measuring apparatus of the type described, comprising four trapping means arranged in two pairs, four latches adapted to lock each of the four trapping means respectively, 20 two notches in each trapping means, one or other of which is engaged by the locking latch for such trapping means, and a spring-loaded plunger in connection with each of one pair of trapping means to enter the notches not occupied by the 25 latches for such pair of trapping means.

WILLIAM POOL.

CERTIFICATE OF CORRECTION.

Patent No. 2,070,749.

February 16, 19

WILLIAM POOL.

It is hereby certified that error appears in the printed specification of the above numbered patent requiring correction as follows: Page 2, second column, line 53, for the word "and" read to; and that the said Letters Patent should be read with this correction therein that the same may conform to the record of the case in the Patent Office.

Signed and sealed this 23rd day of March, A. D. 1937.

Henry Van Arsdale
Acting Commissioner of Patents.
